(57) **CLAIM**

The ornamental design for a beverage cup lid, as shown and described.

DESCRIPTION

FIG. 1 is a perspective view of a beverage cup lid of the present invention;

FIG. 2 is a front view thereof;

FIG. 3 is a rear view thereof;

FIG. 4 is a right side view thereof;

FIG. 5 is a left side thereof;

FIG. 6 is a top view thereof;

FIG. 7 is a bottom view thereof; and,

FIG. 8 is a perspective view thereof mated to a beverage cup, which is depicted in broken lines.

The broken lines in the drawings depict environmental subject matter only and form no part of the claimed design.
